The ornamental design for a section bar of building materials, as shown and described.

DESCRIPTION

FIG. 1 is a front, left and top perspective view of a section bar of building materials showing my new design;

FIG. 2 is a front, right and bottom perspective view thereof;

FIG. 3 is a front view thereof, the rear view being a mirror image of the front view thereof;

FIG. 4 is a left side view thereof;

FIG. 5 is a right side view thereof;

FIG. 6 is a top view thereof;

FIG. 7 is a bottom view thereof; and,

FIG. 8 is a front, right and bottom exploded perspective view thereof.

The section bar of building materials is shown with a symbolic break in its length. The appearance of any portion of the section bar of building materials between the break lines forms no part of the claimed design.
